United States Patent Office

Des. 218,837

Patented Sept. 29, 1970

218,837

GAME BOARD

Bernard L. Ekman, 4A E. Broadway,
Derry, N.H. 03104

Filed Aug. 11, 1969, Ser. No. 18,623

Term of patent 14 years

Int. Cl. D21—01

U.S. Cl. D34—5

The figure is a top plan view of a game board showing my design. The game board is of conventional thickness.

I claim:

The ornamental design for a game board, as shown and described.
